UNITED STATES PATENT OFFICE

GEORGES GAUTIER AND LÉON LE BOZEC, OF COURBEVOIE, AND RAYMOND DUBOIS, OF ASNIERES, FRANCE

CATHODE FOR ROTARY FLAME ARCS

Application filed April 29, 1929, Serial No. 359,030, and in France May 5, 1928.

Our invention relates to a new form of cathode for rotary flame arcs of the kind described in the U. S. A. Patents No. 1,323,304 of December 2nd, 1919, and No. 1,390,456 of 5 September 13th, 1921.

The older apparatus comprises a hollow ring-shaped metallic cathode so-called ring cooled by water or any other cooling fluid. This ring is carried in a support provided 10 on the outside with coils through which passes the arc current. They produce the magnetic field in parallel with the carbon the effect of which is designed to produce the motive power which causes the arc flame to 15 rotate about the crater.

This arrangement is most advantageous for low intensities (25 amperes for example) but in the case of higher intensities the steadiness is not satisfactory. It has been 20 found that this is due to the great tendency on the part of the flame to rotate on the front part of the cathode, as electrodynamic forces tend more and more to cause the lengthening of the flame towards the front and the break 25 follows. As these phenomena do not occur with small cathodes used under 25 amperes it has been thought that the reason of this was the increase in the diameter of the winding that creates the field. The reason appears 30 to be in the distribution of the magnetic field which is more uniform in the middle zone as the diameter of the coils is larger.

The use of coils having the smallest possible diameter produces a field which decreases very rapidly towards the front and the back of the crater, the lines of force of the same diverging on both sides of the middle zone.

In the case of high intensities we utilize 40 thick carbons, a longer arc and a larger water delivery, consequently the cathodes must be relatively large.

Our invention consists in placing the winding which produces the field inside the recess 45 provided for the circulation of the cooling fluid thus allowing the utilization of a winding having a very small diameter.

The space thus lost for the fluid is small because a few coils only of the wire will be 50 sufficient and owing to the strong cooling of

said winding the wire may be fine. Moreover the insulation may be produced without difficulty because the ohmic drop is less than 0,1 volt for this short length of wire. Electrolysis of the water does not take place and the currents shunted through the water constitute a fraction of the main current which may be disregarded. 55

Experiment has shown that the use of an inner winding gives the arc the same configuration for strong and weak intensities, the flame is short, revolves quickly on the middle edge without tending in any way to pass in front of the crater. This gives steadiness to the arc and to the brilliancy, and a luminosity 60 65 to the crater which may be absolutely compared to that of small arcs based on the same principle.

Fig. 1 of the appended drawing is a diagrammatic sectional view which shows by 70 way of example a mode of execution of a cathode according to the present invention.

Fig. 2 is a vertical, central section thereof.

As will be seen in said drawing the winding E having one end connected in solid contact at b, by soldering or in any suitable manner is container in the ring shaped part a in which the cooling fluid circulates, the other end of said winding passing out of the ring through a stuffing box c the water tight packings of which are insulating. 75 80

Having thus described our invention, what we claim and desire to secure by Letters Patent is:

1. A cathode for rotary flame arc which 85 comprises a hollow annular ring and a winding within the same, the axis of said winding being that of the ring, the winding being connected to said ring for the passage of the electric current thereto.

2. A cathode for rotary flame arc which 90 comprises a hollow annular ring in which a cooling fluid flows continuously and a winding immersed in said fluid, the electric current flowing through said winding the axis of 95 the latter being the same as that of the ring.

3. A cathode for rotary flame arc which 100 comprises a hollow annular ring with inner circulation of a cooling fluid and a winding placed in the interior of the ring through

which said fluid flows, the axis of the winding being the same as that of the ring, and the winding being connected at one end in solid contact with the ring while its other end passes out of said ring through a stuffing box.

5 In testimony that we claim the foregoing as our invention we have signed our names.

GEORGES GAUTIER.
